UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

COMBINED BROADCAST RECEIVING AND TELEPHONE SYSTEM.

Application filed October 27, 1922. Serial No. 597,422.

To all whom it may concern:

Be it known that I, EDWARD E. CLEMENT, citizen of the United States, residing at Washington, in the District of Columbia, 5 have invented certain new and useful Improvements in Combined Broadcast Receiving and Telephone Systems, of which the following is a specification, reference being had therein to the accompanying drawing.

10 My invention relates to radio broadcast distributing systems and more particularly to a combined radio broadcast in distributing and telephone system.

15 The object of the present invention is to provide a simple and effective system for distributing or relaying broadcast waves from a central office to subscribers, with supervision at the central office of the reception at any subscriber's substation, and to accomplish this result without additional line conductors and without change in the telephone exchange plant proper.

20 I attain my object by receiving modulated broadcast carrier waves at the central station, amplifying and distributing the same at superaudio frequencies over the subscribers' wired lines, demodulating the carriers at the subscribers' stations and when 25 desired sending back the resultant audio frequency waves over any subscriber's line to central, where they may be caused to energize a suitable audio frequency receiver for purposes of observation, supervision and test. The subscribers' instruments are stand- 30 ardized, and under ordinary circumstances need no tuning.

35 The invention is illustrated in the accompanying drawings in which Fig. 1 is a schematic diagram showing a central office and one subscriber's line. Fig. 2 is a similar 40 diagram of a modified form of radio receiving apparatus for the central office for changing the wave length transmitted to the subscribers. Fig. 3 is a front view and 45 Fig. 4 is a side view of a convenient form of subscriber's instrument modelled on the ordinary telephone desk set; Fig. 5 is a diagrammatic view of the same showing the 50 circuit connections. Figs. 5^a and 5^b are views similar to Fig. 5, showing radio amplification and audio amplification respectively on the line side of the coupler, whereby the 55 desk set is reduced to its simplest elements.

Referring to the drawings, in Fig. 1, the apparatus to the left of the vertical dotted

lines is situated at the central office, that to the right is at the subscriber's station while the connection indicated between the dotted lines is the line connection.

The telephone exchange system assumed 60 herein to be used in carrying out my invention is the standard Western Electric No. 1 switchboard circuit with the usual standard Western Electric substation apparatus.

65 The part of the usual telephone exchange system here shown comprises the subscriber's substation apparatus A connected by conductors 1 and 2 to the conductors 3 and 4 of the line B terminating at the central office C through the wires 5 and 6 on multiple 70 jacks 7. Radio broadcast waves from other stations are received at the telephone central station C by the receiving or antenna circuit 8, from which the broadcast waves are amplified and relayed onto the wires 3—4 75 of the subscriber's line circuit B through known or other suitable amplifying and coupling means such as the amplifying system indicated at 9 and the switch 10. Other switches such as 11 are connected with the 80 amplifier 9 in multiple with the switch 10 for the purpose of connecting to other subscribers' lines.

85 For broadcasting directly from the central office a transmitting circuit of any known or other suitable form is provided at the central office, such as the transmitting circuit 12 with modulating transmitter 13 coupled by means of the coupling coil 14 to multiple switching means such as the 90 plugs 15 and 16 through which the transmitting circuit may be connected with any subscriber's line through local broadcast jacks such as the jack 17 multiplied onto the 95 subscriber's line extension 5—6.

100 Either relayed or local broadcast is put on to the subscribers' lines at super-audio frequency and at sufficient amplitude to enable demodulation to be accomplished and effective audio frequency currents to be thereby produced at the subscribers' substations with simple detector sets which may be of any known or other suitable form such as the crystal detector type, indicated at 18. The detector circuit 18 is arranged to be connected with either the telephone head set 19 or the supervisory coupling means 20, through a double-pole double-throw switch 21, at the will of the subscriber. The use of 105 the double-throw switch has the advantage 110

of effecting an automatic disconnection of the head telephone 19 upon connection of the detector circuit with the test coupling so that all the energy will go into the latter, although, if desired, the head telephone may be permanently connected and the test coupling simply connected in shunt when wanted.

To enable the reception at the subscriber's substation to be supervised from the central office, a supervisory circuit 22 is provided at the central office arranged to be connected with any subscriber's line through suitable switching means such as the plug 23 adapted to engage with a jack such as 24 connected in multiple to the subscriber's line extension 5-6. The supervisory circuit 22 may be of any suitable type, preferably that used with the Western Electric 20 No. 1 switchboard system, the essentials being that it contains means for calling the subscriber such as the ringing key 25, and a listening and talking set 26 and listening key 27. The supervisory coupling 20 at the 25 subscriber's substation is preferably arranged to be normally disconnected from the line and to be connected therewith at will through a suitable switch such as 28. The operator may have a special listening 30 set, as indicated at 26^a connected to the plug 23 through an amplifier 26^b and key 27^a of usual construction, so that the return currents through the line to central will be strengthened. Such amplifiers or electron 35 tube relays are well known and need no description. I believe this combination to be new and original with me.

In operation, broadcast waves received and amplified are put onto the subscribers' 40 lines such as 3-4 at the central station C, either directly by means of the local set 12 or indirectly by means of the relay set 8-9 and a subscriber at substation A wishing to receive the broadcast matter listens in by 45 means of the detector circuit 18 and telephone 19. During the broadcasting if the supervisory operator desires to test the quality of reception at substation A he plugs in on the line at 23-24 and depresses the 50 ringing key 25 whereupon the subscriber at A is signaled in the usual manner. The subscriber at A responding is instructed to reverse switch 21 and close switch 28, which thereupon disconnects the audio circuit of 55 the detector from the receivers 9 and connects it with the line extension 1-2 by way of conductors 29-30, coupler 20 and switch 28, from whence the circuit is extended over the line conductors 3-4, line extension 5-6, 60 jack and plug connection 24-23 and listening key 27 to the supervisory operator's listening set 26. The operator now listening in on the reception at the subscriber's 65 substation can ascertain the quality thereof and if he finds it defective can judge of the

cause of such defect. For example he can discern the effects of static, induction from power lines, cross talk from telephone lines, loose connections, etc.

In Fig. 2 I have shown a radio receiving 70 circuit 8^a, connected to usual radio amplifier and detector apparatus 9^a, which in turn is connected to an audio amplifying set 9^b, connected to a modulator and transmitting set 9^c, having its output side terminating on switching means such as plugs for connection to line circuits. The principle involved herein is that of receiving at one frequency and relaying onto the subscribers' lines at 75 a different frequency. The transmitter 8^c 80 and the receiver 8^a-9^a are capable of being separately tuned, in a manner well understood in the art, which is important as an element in this invention, because all my subscribers' instruments are standardized 85 and flat tuned, that is, all are permanently tuned on the same frequency, which is the normal transmitting frequency of the central office to which they are connected for service. The range of tuning is immaterial. 90

In Figs. 3 and 4 I have shown a form of subscriber's desk instrument embodying the elements, 18, 19, 20, 21, and 28 of Fig. 1. The base 34 is hollow, and the detector set 18 with coupler 20, is arranged therein with suitable circuit connections through cords 42-43 or through ordinary wiring. If cords are employed, the mutual capacity of the conductors must be neutralized or minimized so as not to interfere with 100 reception of the high frequency waves by the detector set. On base 34 is erected a column 32 carrying a switchhook 31, controlling contacts within the column and shown in the diagram Fig. 1 at 31. This hook 105 when down disconnects the entire set from line, and when up connects the set through wires 42-43 to line. Two manual switches 21 and 28 are mounted on the base with contacts preferably within the same, to control the listening set connection to 19 and the cut-back to central at 29-30. A horn 33 is mounted on the upper end of the column, with coupling nipples 33^a arranged on opposite sides of its neck for receiving the 115 two head telephones 19 when the subscriber prefers to listen in that way. Tuning handles of any desired form may be also arranged on the outside of the base as shown at 18^a. 120

The foregoing arrangement is flexible and will lend itself to various detailed forms of subscriber's instruments. For example, the cord connections of the radiophone set 18-19 may be dispensed with, as indicated in 125 Figure 5. The line connections 42-43 here terminate in the primary coil 18^a, of which the secondary 18^b is carried on the instrument, conveniently in the base thereof. Coil 18^a may be enclosed in a casing as indi- 130

cated in dotted lines, and the instrument adjusted with reference thereto either over it, or to one side. Several instruments and several secondaries may be used if desired with 5 a single primary. In this case I have shown a tube detector 18^c with A and B batteries and tuning condenser all enclosed within the instrument body. Tubes suitable for this purpose are commercially available, and 10 small batteries are also on the market, either storage cells or dry batteries. In order to provide a higher B battery voltage than is attainable with an enclosed battery, a separate battery is provided for connection in 15 series to the desk set battery through a cord and a series plug and jack of usual type as indicated at 50 in Fig. 5. In any case the receiver 19 is connected to the instrument circuits through a cord, which for simplicity 20 of illustration is omitted in Figs. 3 and 4, but is indicated in Fig. 5. The mechanical parts are numbered the same in Fig. 5 as in Figs. 3 and 4, the outline only of the desk stand or casing being shown in dotted lines. 25 It is to be understood that super audio frequency or audio frequency amplifying means, or both, may be added to the receiving set without departing from the scope of my invention. Where the detached or loose 30 coupled form of instrument shown in Fig. 5 is employed, the arrangement of Fig. 5^a may be used, where the super audio frequency amplification may be between the line connections 42—43 and the primary winding 35 18^a, and audio frequency amplification means may be mounted on or in the instrument unit. A further modification is that indicated in Fig. 5^b, which is accomplished by connecting to the line wires 42—43 a complete 40 detector set including super audio frequency and audio frequency amplifying tubes, detector coils and tuning devices, with the primary winding of an audio frequency transformer or inductorium of any suitable 45 form arranged the same as coil 18^a. The instrument would then carry the secondary of said inductorium, the receiver, and a wire connection to the receiver, only. Various 50 other modifications will suggest themselves to those skilled in the art, and it is to be understood that I contemplate all such non-essential changes or modifications as fall fairly within the scope of the appended 55 claims.

55 I do not claim herein the following:

(1) A subscriber's desk set shown in Figs. 3, 4, 5, 5^a and 5^b nor the manner of coupling it to the line, the same being claimed in my copending divisional applications, Ser. No. 681,992, filed December 21, 1923, and Ser. 60 No. 47,547, filed August 1, 1925.

(2) The broad idea of a circuit composed of a plurality of transmission links at different frequencies, related to the same line

conductors, the same being claimed in my co-pending application Serial No. 681,991, filed December 21, 1923.

Having thus described my invention what I claim is:

1. The combination with a telephone exchange system having a central office, subscribers' substations, and line circuits connecting the substations with the central office; of means for transmitting modulated super audio frequency carrier currents from 70 the central office over a subscriber's line circuit to the subscriber's substation, detector means at the substation for demodulating the same, means for passing the result—and audio frequency currents to line, and means 75 at the central station responsive to said audio frequency currents, whereby a central station operator may listen in on the subscriber's receiving apparatus.

2. The combination with a telephone exchange system having a central office, subscribers' substations, and line circuits connecting the substations with the central office, of means for transmitting modulated super audio frequency carrier currents from 90 the central office over a subscriber's line circuit to the subscriber's substation, a demodulating receiver at the substation, and means whereby an operator at the central office may 95 listen in directly on the output side of the subscriber's receiver over the line circuit.

3. The combination with a telephone exchange system having a central office, subscribers' substations and line circuits connecting the substations with the central office; of means for transmitting modulated super audio frequency carrier currents over a subscriber's line circuit to the subscriber's substation, detector means at the substation for demodulating the same, a 100 telephone receiver at the substation connected with the output side of the said detector, means for connecting said output side of the detector with the line for transmitting audio-frequency currents back over the line, and a supervisory circuit at the central office comprising signaling, listening and talking means arranged to be connected with any subscriber's line for signaling and 105 talking to the subscriber and listening in on the audio-frequency currents sent back over the line from the substation.

4. The combination with a telephone exchange system having a central office, subscriber's substations and line circuits connecting the substations with the central office; of means for transmitting modulated high frequency carrier currents over a subscriber's line to the subscriber's substation, detector means at the substation for demodulating the same, means for connecting the output side of the subscriber's detector with the line, and supervisory audio-fre- 110 115 120 125

quency receiving and amplifying means at the central station arranged to be connected with the subscriber's line.

5. In a telephone exchange system, a central office, a plurality of subscribers' substations, line circuits connecting the substations with the central office, means at the central office for establishing a connection for telephone currents between any two subscribers' substations, means also at the central office for transmitting modulated superaudio frequency currents over the line circuits in multiple to the substations, and means at the substations to demodulate the same and to reproduce the sound waves represented thereby, the receiving apparatus at all said subscribers' stations being standardized and having a tuning operatively fixed to one and the same predetermined frequency, and the transmitting apparatus being adjustable for tuning to said frequency.

6. The combination with a telephone exchange system having a central office, subscribers' substations and lines connecting the substations with the central office, radio receiving instruments connected to the line circuits at the subscribers' stations, and cooperating tuned superaudio current transmitting means at the central station said receiving instruments being tuned to the frequency of the central office transmitting means and means at the central office for receiving radio communication at any one of a plurality of frequencies and relaying it at the frequency of the central office transmitting means.

7. The combination with a telephone exchange system having a central office, subscribers' substations and lines connecting the substations with the central office, radio receiving instruments connected to the line circuits at the subscribers' stations, and cooperating tuned superaudio current transmitting means at the central station, said receiving instruments being tuned to the frequency of the central office transmitting means, and means at the central office for receiving radio communication at another frequency and relaying it at the frequency of the central office transmitting means.

8. The combination with a telephone exchange system having a central office, subscribers' substations, and line circuits connecting the substations with the central office, carrier current receiving instruments

connected to the line circuits at the subscribers' substations, and tuned carrier current transmitting means at the central office, said receiving instruments being tuned to the frequency of the central office transmitting means and being standardized, and means at the central office for receiving modulated carrier waves radiated at various frequencies, and relaying the same modulations on a carrier wave of a constant given frequency over the subscribers' lines.

9. The combination with a telephone exchange system having a central office, subscribers' substations, and line circuits connecting the substations with the central office, radio receiving instruments at the subscribers' substations, and tuned carrier current transmitting means at the central office, the receiving instruments being tuned to the frequency of the transmitting means and standardized, and means at the central office for receiving modulated carrier waves radiated at various frequencies and for relaying the same modulations over the subscribers' lines on a carrier wave of the frequency of the central office transmitting means, said central office receiving means being equipped with variable tuning devices for selective reception from sending stations employing different frequencies in transmitting, and separate relay tuning means for maintaining the relay transmitting means tuned to the constant frequency common to the subscribers' receiving means.

10. In a telephone exchange system, subscribers' station circuits, a central office, line circuits connecting them, the subscribers' station circuits being coupled to said line circuits and said line circuits being adapted to carry modulated high frequency waves into the subscribers' stations, the line circuits being all tuned to the same frequency and forming a plurality of tuned paths in parallel with respect to the central office, means for controlling the subscribers' station circuits of such nature that operation thereof tends to cause detuning of the tuned paths, and means in the connection between said control means and the line circuit for preventing such detuning.

In testimony whereof he hereunto affixes his signature.

EDWARD E. CLEMENT.
